RELAY

Elmer Borgkvist, Arlington, N. J.

Application January 6, 1937, Serial No. 119,180

10 Claims. (Cl. 200—165)

The present invention is directed to a relay switch in which the various parts of the switch are so arranged as to enable a quick assembly of the switch. In actual practice, it has been found 5 commonly expedient to have the individual parts of the switch bear such a relationship to each other so that they may easily be assembled, thus creating a considerable savings in time during the process of manufacture.

10 A further object of the invention is present in the compact arrangement of the various parts which results in a relay that will take as little space as possible. A savings in space has been accomplished especially in that part of the relay 15 which comprises the switch portion for closing an external circuit. This advantage of compactness is naturally important wherever the question of space requirements may enter.

A further object of the invention lies in the few 20 and simple parts which are necessary to the complete organization of the switch relay, which becomes a material factor as far as cost for the manufacture of such relays is concerned.

Further and other important objects will be 25 apparent as the description of the invention proceeds as illustrated in the following figures:

Figure 1 is an elevational view in section of the switch relay showing details of the interior constructions;

30 Fig. 2 is a partial view in side elevation taken of Fig. 1 looking toward the left;

Fig. 3 is a plan view of Fig. 1;

Fig. 4 is a sectional plan view taken through the plane 4—4 of Fig. 1; and

35 Fig. 5 is a sectional plan view through the plane 5—5 of Fig. 2.

In the embodiment of the invention illustrated, an outer casing 1 of insulating material, preferably pressed fiber, houses the relay and switch mechanism. A reel comprising a hollow core or 40 inner tubing 31 of insulating material and end flanges 7, 32, has wound upon it the magnetic coil 2 as in ordinary magnetic coil constructions. Within the tubing 31 is a solenoid rod or armature 3 which is preferably of cold-drawn steel. Attached to the solenoid rod 3 by a pin 9 is a portion 8 of brass rod (or other suitable non-magnetic material). The purpose of the portion 8 of the rod is to give sufficient weight to the 45 armature so that in normal position with the magnetic coil 2 deenergized or only slightly magnetized, the solenoid rod 3 will assume the lower position shown in Fig. 1. Fixed to the brass rod 8 is a brass headed pin 11 for slidably supporting the disc 10. The member 10 is normally held

against the head of the pin 11 by means of an intermediate spring 12 bearing on the brass rod 8 and the member 10. The member 10 may be constructed as a disc, as shown in the drawing, or may consist of a transverse bar or some other element adapted to be reciprocated longitudinally in the housing.

As shown in Figs. 4 and 5, the disc 10 has affixed thereto as by a pressed engagement the contact points 29 and 30. These contact points 10 are preferably of silver. The disc 10 also has apertures 13 and 14 as shown in Fig. 1 which aid to properly guide the movement of the disc.

The top of the housing 1 is closed by an end cap structure. This end cap structure comprises 18 the outer disc 19 and the inner disc 20, each of which is made of insulating materials such as fiber. The discs 19 and 20 are connected together as a unit by means of metallic eyelets 17 and 18. Surrounding the eyelets 17 and 18 and 20 positioned between the discs 19 and 20 are the insulating washers 33 and 34. The ends of the eyelets 17 and 18 are pressed over as illustrated in Fig. 1 so as to form a permanent connection. Extended through the eyelets 17 and 18 are 25 headed guide pins 15 and 16. These pins are preferably made of brass and extend into the apertures 13, 14 of the disc 10. The heads of the pins 15, 16 may be fixedly attached to the eyelets 17 and 18 by means of solder or other well 30 known connecting means. The inner disc 20 has mounted thereon a second pair of eyelets 25 and 26 as shown in Fig. 2. These eyelets are preferably made of brass and are bent over as shown in Fig. 2 to receive the terminals of wires 22, 23 35 of an external circuit. The ends of the wires 22, 23 are held in position by the overlapping edge of the eyelets, although if necessary soldering may be employed to have a strong connection. Contact points 27 and 28 made of silver, are pressed 40 into fixed engagement with the eyelets as shown in Fig. 2 and are normally positioned above the contacts 29 and 30. The inner disc 20 also has a central aperture 25 positioned directly above the head of the pin 11.

It will be understood that the invention is not necessarily restricted to guide means as described but may be of other description within the scope of the appended claims.

The end cap structure may be threaded into the 50 end of the housing 1 by means of threads, such as 21 of Fig. 1, or may merely have a pressed relationship with the outer housing structure 1. The base of the housing 1 has an insulating closure 6 for the bottom of the core 31. Lead-in wires 55

4 and 5 are connected to the magnetic coil 2 in the customary manner.

The assembly of the relay switch mechanism is exceedingly simple, in so far as it is necessary to merely remove the end cap structure in the form of washers 19 and 20. The armature 3 and its associated disc 10 are then inserted within the housing 1 and assume the position shown in Fig. 1. With the armature so positioned, the end cap structure is replaced thus forming the complete relay switch mechanism.

In the operation of the device with the relay assuming a vertical position as shown in Fig. 1, the armature 3 normally assumes a lower position as shown. When the magnetic coil 2 is sufficiently energized, the armature rod 3 is lifted upwardly until the contact points 29 and 30 on the disc 10 engage the contact points 27 and 28 on the end cap structure. Such engagement of contact points completes the external circuit of wires 22, 23. After the engagement of the contact points, the rod 3 may continue its upward movement slightly so that the head of the pin 11 will move independently of the disc 10 into the space created by the opening 35 in disc 20. When the magnetic coil 2 becomes sufficiently deenergized, the armature rod 3 due to its own weight and the weight of the section 8 will drop into its lower position, as shown in Fig. 1. The purpose of the guide pins 15, 16 and the apertures 13, 14 is quite obvious in so far as they prevent any rotary movement of the disc 10 which would disalign the contact points 27, 28 with respect to the contact points 29 and 30.

The particular construction of the end cap with the eyelets positioned as shown enables a very compact switch structure. Also the arrangement of the switch disc member 10 and its relationship to the armature rod 3 and end cap structure 19, 20 makes a more compact arrangement. The device is simple in its arrangement of parts and has been found commonly expedient.

It is not my intention to limit the present invention to the preferred embodiment illustrated, but rather to include all equivalent structures as covered by the scope of the following claims.

I claim as my invention:

50. 1. In a relay of the class described, having a magnetic coil for actuation of an armature rod, both of which are encased within an insulated housing, the combination of a disc connected to said rod at one end, an end cap for the housing comprising a pair of inner and outer insulating discs the inner disc bearing switch points and the outer disc bearing guide pins, apertures in the disc to receive the guide pins, and switch points on the disc to engage the switch points on the inner disc of the end cap when the magnet coil is sufficiently energized.

65. 2. In a relay of the class described, having a magnetic coil for actuation of an armature rod, both of which are encased within an insulated housing, the combination of a headed pin fixed to one end of the rod, a switch disc slidably mounted for longitudinal movement only on said pin, means for yieldably holding the disc against the head of the pin, an end cap for the housing comprising a pair of inner and outer insulating discs the inner disc bearing switch points and the outer disc bearing guide pins, apertures in said switch disc to receive the guide pins, and switch points on said switch disc to engage the switch points on the inner

disc of the end cap when the magnet coil is sufficiently energized.

3. In a relay of the class described, having a magnetic coil for actuation of an armature rod, both of which are encased within an insulated 5 housing, the combination of a headed pin fixed to one end of the rod, a switch disc slidably mounted for longitudinal movement only on said pin, a spring mounted on the pin interposed between the armature and the disc for yieldably holding the disc against the head of the pin, an end cap for the housing comprising a pair of outer and inner insulating discs, the inner disc bearing switch points and the outer disc bearing guide pins, apertures in said switch disc to receive the guide pins, and switch points on said switch disc to engage the switch points on the inner disc of the end cap when the magnet coil is sufficiently energized.

4. In a relay of the class described, having 20 a magnetic coil for actuation of an armature rod, both of which are encased within an insulated housing, the combination of a headed pin fixed to one end of the rod, a switch disc slidably mounted for longitudinal movement only 25 on said pin, means for yieldably holding the said switch against the head of the pin, an end cap for the housing comprising a pair of inner and outer insulating discs, the inner disc bearing 30 switch points and the outer disc bearing guide pins, apertures in said switch disc to receive the guide pins, switch points on said switch disc, and an aperture in the end cap for receiving the head of pin when the switch points on the disc engage the switch points on the inner disc of 35 the end cap.

5. An end cap for a relay switch device, comprising inner and outer insulating discs, a pair of eyelets for connecting said discs, a guide pin positioned through each eyelet and affixed thereto, a second pair of eyelets attached to the inner disc only, contact points and circuit connections attached to the latter eyelets.

6. An end cap for a relay switch device, comprising inner and outer insulating discs, a pair 45 of eyelets for connecting said discs, insulating washers surrounding the eyelets for spacing the discs, a guide pin positioned through each eyelet and affixed thereto, a second pair of eyelets attached to the inner disc only, contact points and 50 circuit connections attached to the latter eyelets.

7. An end cap for a relay switch device, comprising inner and outer insulating discs, said inner disc being centrally apertured, a pair of 55 eyelets for connecting said discs, a guide pin positioned through each eyelet and affixed thereto, a second pair of eyelets attached to the inner disc only, contact points and circuit-connections attached to the latter eyelets.

8. In a relay of the class described having a magnetic coil for actuation of an armature rod, both of which are encased within an insulated housing, the combination of a switch disc yieldingly connected to said rod for longitudinal movement only, an end cap for said housing comprising a pair of inner and outer insulating discs, the inner disc bearing switch elements and the outer disc bearing guide means, said guide means being associated with the said switch disc for 70 preventing rotation of the latter.

9. In a relay of the class described having a magnetic coil for actuation of an armature rod, both of which are encased within an insulated housing, the combination of a switch disc yield- 75

ingly connected to said rod for longitudinal movement only, switch points affixed to said switch disc, an end cap for said housing comprising a pair of inner and outer insulating discs, the inner disc bearing switch points and the outer disc bearing guide means, said guide means being associated with said switch disc for positively aligning the switch points.

10. In a relay of the class described having a magnetic coil for actuation of an armature rod,

both of which are encased within an insulated housing, the combination of a switch member yieldingly connected with said rod for longitudinal movement only, an end-cap for said housing having guide means for guiding said switch member to prevent rotation thereof and comprising a pair of inner and outer insulating discs, the inner disc bearing switch elements to contact said switch member.
